UNITED STATES PATENT OFFICE.

JOHN C. QUINN, OF PORT RICHMOND, NEW YORK, ASSIGNOR TO QUINN OIL BURNER CORPORATION, OF NEW YORK, N. Y., A CORPORATION OF NEW YORK.

OIL BURNER.

Application filed October 11, 1923. Serial No. 667,883.

This invention relates to certain new and useful improvements in hydro-carbon burners adapted to burn in stoves, furnaces, etc., the coarser grades of crude oil, and is an improvement on the invention for which I made application for Letters Patent on the 7th day of November, 1923, Serial No. 599,534.

The present invention consists in certain novel features of construction and arrangement of parts, which have been worked out in practice since the filing of the above case, which will be readily understood by reference to the description of the drawings 15 and to the appended claims.

One of the objects of my invention is to avoid the use of a solid metal spreader or baffle plate and the reason for this is that such a baffle plate always becomes covered with soot which by its presence tends to poor combustion and eventually to more or less imperfect action in the operative process of producing gas from oil. Because of the peculiar construction of my device with 25 an additional air supply introduced through a tubular air intake member, a strong draft is created which impinges against the upward flow of the mixture exterior thereto, whereupon the flame is spread in an almost horizontal plane as by a baffle plate, yet entirely without the use of one. In this manner the impedance 30 of the gas against such plate is entirely avoided and the creation of soot thereby, such as occurs in the use of the usual 35 spreader is entirely obviated.

Another object of my invention is the provision of a vaporizing plate so located and positioned that it will act in the manner of a closed retort, although it is really not one, for it is not in any manner fastened to the base plate but simply rests lightly thereon, and is in no way resistant to the 40 action of explosive forces of the gases 45 should they become improperly ignited.

A further object of my invention is to provide a hydro-carbon burner which produces a gas similar to producer gas, that is to say, a gas mixed with an insufficient amount of air to produce combustion whatever 50 may be the adjustment of the burner, until the mixture as it ascends, reaches a

point where an additional supply of air is added thereto sufficient to render the mixture thoroughly combustible. This I accomplish by means of a tubular air supply pipe which rises in the midst of the surrounding inert mixture and discharges into it an additional supply at a point somewhat above the surrounding burner through which 60 said supply pipe protrudes, whereupon combustion immediately takes place.

For the purpose of illustrating the invention, a preferred form thereof is shown herewith, this form having been found to give satisfactory and reliable results, although it is understood that the various instrumentalities of which the invention consists can be differently arranged and organized. It is to be understood further that the invention is not limited to the precise arrangement and organization of the instrumentalities as herein shown and described, except as limited by the scope of the appended claims.

In the drawings:

Fig. 1 is a perspective view showing the general arrangement of my improved burner set up in a heating furnace with its tanks and connecting piping as the same appears in the cellar of a modern house;

Fig. 2 is a transverse sectional view of the burner;

Fig. 3 is a vertical sectional view on the line 3—3 of Fig. 2;

Fig. 4 is a horizontal staggered sectional view on the line 4—4 of Fig. 2; and

Fig. 5 is a detail perspective view of the cone detached from the rest of the structure.

Corresponding and like parts are referred to in the following description and indicated in all the views of the drawings by the same reference characters.

The numeral 1 refers to a furnace or hot water boiler of the usual or any improved type, which is provided with a smoke stack 2 extending into the chimney of the house. The body of the furnace is provided with an upper member or top 3 having a steam pressure diaphragm 4 and a pressure gauge 5. The diaphragm 4 has a fulcrum 6 in which rests a lever 7 pivotally attached at one end to an upright 8 whose base 9 is secured to the top of the furnace. The lever has sev-

eral notches 11 provided thereon upon which is hung an iron weight 12 by means of a strap 13. To the free end 14 of the lever is pivotally secured a bell crank lever 15 whose other end 16 descends towards the bottom of the stove 17 where it is pivotally secured to the stem 18 of a valve in the coupling 19, the purpose of which is to lessen the flow of oil through the supply pipe 21 from the small tank 22 to the burner when the steam pressure becomes excessive. The supply pipe 21 at a point a little nearer the tank is provided with a second coupling 23 having a valve seat therein. The stem 24 thereof is medately attached to a balance rod 25 having a weighted ball 26 hanging from one end and a can 27 from the other end into which opens the free end of an overflow supply pipe 28, (see Fig. 2). It will be noticed that when the weight of the oil from the overflow supply pipe into the can 27 overbalances the ball 26, the valve is closed, shutting off the flow of oil from the tank 22, and the flame of the burner is extinguished.

The small supply tank 22 is provided on its under surface with an ordinary globe cut off valve 30 by means of which its supply to the furnace may be cut off, and upon its upper surface is provided with a supply pipe 31 and an overflow pipe 32. The large supply tank 33 is provided with a supply pipe 34 from which the oil is delivered into the cellar from the outside, and an overflow pipe 35 through which the oil exists on the outside of the house should the tank become oversupplied, and to this pipe 35 is also connected the oversupply pipe 32 from the small tank. Upon the top of the larger tank is secured any suitable pump mechanism 36 for pumping the oil into the supply pipe 31 of the smaller tank 22, but as these features form no part of my invention, they will not be further described.

Centrally located upon the grate bars 40 of the furnace by means of headed bolts 41 and nuts 42, is my improved burner, the same consisting of a base plate having cast integrally therewith on its exterior edge, an upper cylindrical wall 43 having at equidistant intervals several supporting bars 44. Each of the supporting bars is cut away on its upper exterior wall, as at 45, and at the base of such supporting bars the metal flares outwardly into the flanged plates 46 which are perforated for the reception of the binding posts 47 which hold together the body of my structure and the right angled annular flange 48 which is provided with apertures 49 for the reception of said posts. Said flange on its interior is provided with a shoulder 51 upon which latter the cone 52 is adapted to seat itself, receiving additional support from the top of the supporting bars 44.

Cast integrally with the base plate is a tubular member 53 which extends up through the center of the cone to a point somewhat beyond said cone and other portions of the device and is provided with a detachable cap 54 which will be hereinafter more fully described.

The floor of the base plate 55, as more clearly seen in Fig. 4, is provided with an inner annular groove 56, an outer annular groove 56', an annular ridge 57, and at a point 57' with a depressed oil passage 58 by means of which the oil in the exterior groove 56' may enter into the interior groove 56. As oil, like any other liquid, seeks its own level, the arrangement of the grooves enables my improved burner to be properly levelled and positioned in the furnace, and gives also an even distribution of oil in the central portion of the base. The cylindrical wall 43 is provided on one side with a boss 59 integrally cast therewith. This boss is drilled or pierced with two orifices, one above the other, the lower one of which is for the reception of the fuel oil supply pipe 21 and the upper one for the reception of the fuel oil overflow pipe 28.

Referring again to my improved burner, attention is particularly invited to the description of the floor of the base in connection with my vaporizing plate or retort 60, which consists of an annular plate 62 provided with a central opening 63 which enables it to be fitted over the tubular air inlet member 53. It is further provided on its lower peripheral edge with a downwardly extending ridge 64. It is to be noted that the outer groove 56' of the base, or that part between the lower portion of the cylindrical wall and the ridge 57 in the base is to be filled with cement and the vaporizing plate positioned in place and pressed down upon the ridge so that its downward ridge may become indented in the cement while wet, whereupon the vaporizing plate is removed and the cement allowed to dry out and harden in place with said indent therein, after which the vaporizing plate is again placed in position. This cement plug or block at the far end prevents the gas from escaping at that point and directs the hot point to the base of the tubular member, thereby greatly augmenting its draft.

In the arrangement mentioned lies a very important feature of my invention for by this construction we have oil in the groove 56 between the tubular air inlet member and the ridge 57 in the base, and the base is thus practically a retort. On the other hand, the vaporizing plate and base do not constitute a retort because said vaporizing plate is loosely mounted and unattached at any point to the base, and is thus non-resistant to any explosive force of gases which may arise. The upper side of the vaporizing

plate is provided on each side of the center with a holding lug 61, by means of which the plate may be turned or lifted.

Reference is now made to Figure 5, showing the cone detached, and to Figure 3, showing the cone resting in its proper position upon the interiorly extending flange or seat 51 and the upper ends of the supporting bars 44.

10 The body of the cone is indicated by the numeral 65. It is of circular formation, gradually flaring as it ascends, and decreasing as it descends until its lower edge is within the upper cylindrical wall 43,

15 while its flaring upper edge is of a size to fit loosely within the interior periphery of the circular right angled flange 48. The upper surface of the cone is provided on its upper edge with a turning lug 67 by means

20 of which the same may be turned or lifted. The under surface of the cone 65 is provided with a series of three inclined edges 67', the lower edge of each of which is formed into a double cam, the first of which

25 ends in an abrupt notch 71 and the latter of which similarly terminates in another abrupt notch 72. Each of the three cams is of like construction and size, and by means of the turning flange 67, the cone can be turned

30 in a gradually ascending or descending circle from the point 73 to 74 and again from point 74 to the still higher point 72, enabling the operator to gradually vary the size of the opening between the vaporizing plate

35 and the lower edge of the cone, thus lessening or increasing the draft. From the above it will be seen that the regulation of the cone is such as to permit of a wide entrance for the air between these points, in

40 which event the clearance being much, the draft will be small. On the other hand, if the regulation is such as to bring about a rather small clearance, then the draft is strong, and through the concentration of 45 stack draft in the chimney, the effect of a blower is achieved without the use of any special mechanism for that purpose.

My device has no baffle plate, but upon the top of the tubular member, I place a 50 cap 54, the same consisting of a small solid plate of metal having upon its upper side a holding or lifting plug 76, and the lower part of the plate gradually descending into a point 77. Depending from its lower periphery are three legs, as indicated at 78.

55 The lower inner edge of the legs are somewhat attenuated, as at 79, so as to fit within the interior of the tubular member, permitting the notched edges 80 to sit squarely upon the top of the member, thus leaving a circular air space of less than one-half inch in height all around the top of the tubular member except where the legs rest on the top of said member.

60 In Figure 1 the burner is shown mounted

upon the grate bars of a furnace. The burner is set in the center of the grate bars and the remaining area of such bars is covered with a sheet of metal 82, and the burner is also surrounded by a vertical sheet metal 70 wall 83, as seen in Figure 2. A mixture of concrete 84 is then poured over the sheet metal until it is covered up to the point 85, and the same is allowed to dry. The object 75 of this is to prevent the entrance of any air above the grate bars save that which comes up through and around the burner, as indicated by the arrows in Fig. 2, and in this way a strong draft is secured through the tubular air member in the center of the base 80 and also around the exterior and interior sides of the cone and up through the cone to the top of the burner.

The operation of my device is as follows: 85 The oil being turned on, enters through the fuel supply pipe 21 upon the base of the burner, the groove 56', and through the depressed channel 58 goes directly into the inner groove 56 and through the circular opening through which the tubular member rises, and to the upper surface thereof of the vaporizing plate. A lighted rag covered with oil is then thrown upon the plate and for the space of a minute there is 90 considerable smoke arising from the imperfect combustion due to the cold condition of the furnace. This, however, is immediately succeeded by perfect combustion 95 and the entire absence of smoke, the vaporizing plate rapidly becoming heated 100 and volatilizing the oil into gas. The amount of oxygen supplied to the gas arising from the oil is not, however, sufficient to support combustion. The air coming into contact with the cone becomes 105 heated and mixed with the gas and the effect is to make a mixture somewhat similar to producer gas in that said mixture will not burn, since the quantity of air supplied is 110 insufficient to produce complete combustion. This is the case either when the cone is 115 adjusted to its highest or lowest level and notwithstanding the mixture may have ascended within the cone up to a point adjacent to the outlet of the tubular cone. At this point, however, the air coming up through the tubular member unites therewith, and by means of the cap 54, the draft coming up through the center of the tubular member 120 is diverted practically in a longitudinal plane into the mixture without the tubular member already referred to and the additional amount of oxygen needed to produce perfect combustion is afforded and 125 takes place.

In this connection it may be stated that the ordinary baffle plate or metal spreader heretofore used has been found undesirable and has always interfered with the perfect 130 working of an oil burner. It will be ob-

served, however, that I have no baffle plate, the current of air rising through the tubular member and spreading out by reason of the cap so as to unite with the exterior mixture forms its own baffle plate as it is injected into said mixture and produces combustion without any impedance of gas by such a plate. In other words, in the instant case, the air goes up in a vertical plane through the tubular member and passes out therefrom in a practically longitudinal plane without any impedance of a plate, such as a baffle plate, simply by the force of the air rushing through the tubular member at which moment perfect combustion takes place without the use of a plate.

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention, or exceeding the scope of the appended claims.

I claim:

1. In a device of the character described, the combination with a base plate, a vertical cylindrical wall upon its upper surface, and a loosely mounted vaporizing plate adapted to rest upon the base plate, of a cone, means to support the same above the base plate, openings for the admission of air between the cylindrical wall and the cone, and separate means to furnish an additional supply of air and to so commingle it with the air and gas arising from the vaporizing plate that the flame will spread outwardly.

2. In a device of the character described, the combination with a base plate, a vertical cylindrical wall upon its upper surface, supporting standards rising above the cylindrical wall, and a loosely mounted vaporizing plate adapted to rest upon the base plate, of a cone adapted to rest upon the supporting standards and to depend therefrom, openings for the admission of air between the cylindrical wall and the cone, and separate means adapted to furnish an additional supply of air and to so commingle it with the air and gas arising from the vaporizing plate that the flame will spread outwardly in substantially a horizontal flame.

3. In a device of the character described, the combination with a base plate, a vertical cylindrical wall upon its upper surface, supporting standards rising above the cylindrical wall, and a loosely mounted vaporizing plate adapted to rest upon the base plate, of a cone adapted to rest upon the supporting standards and to depend

therefrom, openings for the admission of air between the cylindrical wall and the cone, and separate means to furnish an additional supply of air and adapted to so commingle it with the air and gas that the flame will spread outwardly.

4. In a device of the character described, the combination with a base plate, a vertical cylindrical wall upon its upper surface, supporting standards rising above the cylindrical wall, and a loosely mounted vaporizing plate adapted to rest upon the base plate, of a cone adapted to rest upon the supporting standards and to depend therefrom, openings for the admission of air between the cylindrical wall and the cone, and separate means to furnish an additional supply of air and adapted to so commingle it with the air and gas that the flame will spread outwardly over the cone.

5. In a device of the character described, the combination with a base plate, a vertical cylindrical wall upon its upper surface, a loosely mounted vaporizing plate adapted to rest upon the base plate, of a cone, means to support the same above the base, openings for the admission of air between the cylindrical wall and the cone, a separate tubular air supply member to furnish an additional supply of air and to so commingle it with the air and gas mixture arising from the vaporizing plate that the flame will spread outwardly.

6. In a device of the character described, the combination with a base plate, a vertical cylindrical wall upon its upper surface, and a loosely mounted vaporizing plate adapted to rest upon the base plate, of a cone, means to support the same above the base plate, openings for the admission of air between the cylindrical wall and the cone, a separate tubular air supply member to furnish an additional supply of air, and an air spreader above the same to so commingle the additional supply of air with the air and gas mixture arising from the vaporizing plate that the flame will spread outwardly.

7. In a device of the character described, the combination with a base plate, a vertical cylindrical wall upon its upper surface, and a loosely mounted vaporizing plate adapted to rest upon the base plate, of a cone, means to support the same above the base plate, openings for the admission of air between the cylindrical wall and the cone, a separate tubular air supply member cast integrally with the base plate to furnish an additional supply of air and to so commingle it with the air and gas mixture arising from the vaporizing plate that the flame will spread outwardly.

8. In a device of the character described, the combination with a base plate, a vertical

5 cylindrical wall upon its upper surface, and a loosely mounted vaporizing plate whose lower edge is provided with a depending ridge and a detent in the base into which the same fits, of a cone, means to support the same above the base plate, openings for the admission of air between the cylindrical wall and the cone, and a separate tubular air supply member to furnish an additional 10 supply of air and to so commingle it with the air and gas mixture arising from the vaporizing plate that the flame will spread outwardly.

9. In a device of the character described, 15 the combination with a base plate, a vertical cylindrical wall upon its upper surface, and a loosely mounted vaporizing plate adapted to rest upon the base plate, of a cone, means to support the same above the base plate, 20 openings for the admission of air between the cylindrical wall and the cone, and a separate tubular air supply member to furnish an additional supply of air and to so commingle it with the air and gas mixture arising 25 from the vaporizing plate that the flame will spread outwardly.

10. In a device of the character described, the combination with a base plate, a vertical cylindrical wall upon its upper 30 surface, and a loosely mounted vaporizing plate adapted to rest upon the base plate, of a cone, means to support the same above the base plate, openings for the admission of air between the cylindrical wall and the 35 cone, and a separate central tubular air supply member to furnish an additional supply of air and to so commingle it with the air and gas mixture arising from the vaporizing plate that the flame will spread outwardly.

40 11. In a device of the character described, the combination with a base plate, a vertical cylindrical wall upon its upper surface, and a loosely mounted vaporizing plate centrally apertured and whose lower 45 edge is provided with a depending ridge and a detent in the base into which the same fits, of a cone, means to support the same above the base plate, openings for the admission of air between the cylindrical wall and the 50 cone, and a separate tubular air supply member to furnish an additional supply of air and to so commingle it with the air and gas mixture arising from the vaporizing plate that the flame will spread outwardly.

55 12. In a device of the character described, the combination with a base plate, a vertical cylindrical wall upon its upper surface, and a loosely mounted vaporizing plate adapted to rest upon the base plate, 60 of a cone provided with a flaring upper edge upon the lower side of which is a depending cam, means above the base plate to support the cone and upon which it may slide, openings for the admission of air between the 65 cylindrical wall and the cone, and a separate

tubular air supply member to furnish an additional supply of air and to so commingle it with the air and gas mixture arising from the vaporizing plate that the flame will spread outwardly.

70 13. In a device of the character described, the combination with a base plate, a vertical cylindrical wall upon its upper surface, and a loosely mounted vaporizing plate adapted to rest upon the base plate, of a cone provided with a flaring upper edge upon the lower side of which is a depending cam divided into two cam like ridges, one of greater diameter or height than the other, means above the base plate to support the 80 cone and upon which it may slide, openings for the admission of air between the cylindrical wall and the cone, and a separate tubular air supply member to furnish an additional supply of air and to so commingle it with the air and gas mixture arising from the vaporizing plate that the flame will spread outwardly.

85 14. In a device of the character described, the combination with a base plate, a vertical cylindrical wall upon its upper surface, and a loosely mounted vaporizing plate adapted to rest upon the base plate, of a cone provided with a flaring edge upon the lower side of which is a series of depending cams, means above the base plate to support the cone and upon which it may slide, openings for the admission of air between the cylindrical wall and the cone, and a separate tubular air supply member to furnish an additional supply of air and to so commingle it with the air and gas mixture arising from the vaporizing plate that the flame will spread outwardly.

90 15. In a device of the character described, the combination with a base plate, a vertical cylindrical wall upon its upper surface, and a loosely mounted vaporizing plate adapted to rest upon the base plate, of a cone provided with a flaring edge upon the lower side of which is a series of depending cams each divided into two ridges, one of greater diameter or height than the other, means above the base plate to support the cone and upon which it may slide, openings for the admission of air between the cylindrical wall and the cone, and a separate tubular air supply member to furnish an additional supply of air and to so commingle it with the air and gas mixture arising from the vaporizing plate that the flame will spread outwardly.

105 16. In a device of the character described, the combination with the base thereof, an inlet for oil, a vaporizer upon the base, a hollow depending member provided on its upper end with a flaring edge, a series of cams on the under side of said flaring edge, and means upon which said member may slide, means for admitting a current of air upon the vaporizer.

- 6
17. In a device of the character described, the combination with the base thereof, an inlet for oil, a vaporizer upon the base, a hollow depending member provided with a cam, and means upon which said member may slide, means for admitting a current of air upon the vaporizer, of an additional centrally located air supply, and means to so disperse said additional air supply as to commingle it with the air and gas arising from the vaporizer to form more perfect combustion.
18. In a device of the character described, the combination with the base thereof, an inlet for oil, a vaporizer upon the base, a wall extending upwardly from the base, a hollow depending member above the base provided with a cam, and means upon which it may slide, means for admitting a current of air upon the vaporizer, an additional air supply, and means to so disperse said additional air supply as to commingle it with the gas and air arising from the vaporizer to form more perfect combustion.
19. In a device of the character described, the combination with the base thereof, an inlet for oil, a vaporizer upon the base plate, a wall extending upwardly from the base plate, a hollow depending member above the base provided with a cam, means for admitting a current of air upon the vaporizer, an additional centrally located air supply, and means to so disperse said additional air supply as to commingle it with the gas and air arising from the vaporizer to form more perfect combustion.
20. In a device of the character described, the combination with the base thereof, an inlet for oil, a vaporizer upon the base, a wall extending upwardly from the base plate, a hollow depending member above the base provided with a cam, an open space above the top of the wall, and an open space between said wall and the side wall of the depending member, means for admitting a current of air upon the vaporizer, an additional air supply, and means to so disperse said additional air supply as to commingle it with the gas and air arising from the vaporizer to form more perfect combustion.

In testimony whereof I affix my signature.

JOHN C. QUINN.
